[57] CLAIM

The ornamental design for a skateboard hanger, as shown and described.

DESCRIPTION

FIG. 1 is a perspective view of a skateboard hanger showing my new design;

FIG. 2 is a front elevational view thereof;

FIG. 3 is a right side elevational view with the left side being a mirror image thereof; and,

FIG. 4 is an environmental rear elevational view thereof. The broken line showing of the partial skateboard in FIG. 4 is for illustrative purposes only and forms no part of the claimed design.
